UNITED STATES PATENT OFFICE

ISIDORE P. SMITH, OF OTTAWA HILLS, OHIO, ASSIGNOR TO THE HETTRICK MANUFACTURING COMPANY, OF TOLEDO, OHIO, A CORPORATION OF OHIO

DESIGN FOR A CANVAS PLAY TENT

Application filed March 14, 1932. Serial No. 43,191. Term of patent 7 years.

To all whom it may concern:

Be it known that I, ISIDORE P. SMITH, a citizen of the United States, and resident of the village of Ottawa Hills, county of Lucas and State of Ohio, have invented a new, original, and ornamental Design for a Canvas Play Tent, of which the following is a specification, reference being had to the accompanying drawing forming a part thereof, showing my new design.

In the drawing,

The figure is a perspective view of a canvas play tent, showing my new design.

The rear wall of the tent is plain, but the left side of the tent is provided with a window, and is otherwise similar to the right side shown on the drawing. The rear portion of the roof of the tent is gabled similar to that shown in the front portion of the roof.

I claim:

The ornamental design for a canvas play tent as shown and described.

In testimony whereof I have hereunto signed my name to this specification.

ISIDORE P. SMITH.
